MEANS FOR STRETCHING OR SHAPING
SOCKS AND SIMILAR FOOT COVERINGSNorris Barker, Johannesburg, Transvaal,
Union of South AfricaApplication August 9, 1946, Serial No. 689,317
In the Union of South Africa August 28, 1945

4 Claims. (Cl. 223—77)

1

This invention relates to means for stretching or shaping socks, stockings and similar footwear or foot coverings. The means or device is applicable for use in stretching or expanding shrunken socks in drying them after they have been washed, so as to impart to them the required shape and size, and also for drying and shaping socks and the like which have been moistened or wetted after manufacture, in order to impart the desired shape and size to the dry and finished product, or, by limiting the amount of or preventing shrinkage when wet, to determine the shape and dimensions of the sock or the like.

The means or device can also be utilized for displaying socks, stockings or the like in shops and other places.

The object of the invention is to provide an improved simple and efficient sock, et cetera, stretcher, shaper or former on which the sock can be easily and quickly placed in position, and which can thereafter be operated or adjusted to stretch the same in the process of drying, shaping or forming it, and to retain it in that condition for a sufficient length of time to cause it to keep its finished shape without contraction or shrinkage.

According to the invention I provide a frame or former shaped to conform more or less to the shape of the toe, sole, heel and back portions of the sock when in a flat condition, and extending forwardly beyond or at the top of the back portion, and a cord or other flexible element or member adapted, when in use, to extend from the toe portion or front of the foot portion of the frame to the forwardly extending portion thereof and to be operated or moved into position to apply suitable tension to the front of the sock to cause it to be stretched or shaped upon and by the frame and cord or member.

Cord or other flexible or resilient means is combined or made integral with the cord or flexible member for limiting its stretching or shaping movement in a forward direction at or near the ankle. Such means may be adjustable so as to vary the extent of such limit, and for this purpose the flexible cord or member may include the limiting means and in its lower portion be of triangular shape and engage, at one angle with the toe portion of the frame, at another angle with the frame near the heel portion thereof, and from the third angle extend upwardly to engage with the forwardly extending portion of the frame. In this case the part of the flexible cord or member, between the point of engagement with the toe portion of the frame and the

2

third angle, may serve to stretch or shape the front of the foot portion of the sock. The triangular portion of the cord or member may be freely movable in relation to the frame to vary the angles thereof automatically, or be detachably fixed at one or both of its points of attachment with the frame.

The forwardly extending portion of the frame may be fashioned with an arcuate or curved top or outer surface to be engaged by a looped portion of the cord or member. The arc or the curved surface may be struck from a centre such that a more or less uniform tension of the cord or member will be maintained when adjusting the looped end portion thereof on the curved surface to stretch or shape the sock.

The invention will be more fully described with the aid of the accompanying sheet of drawings, wherein two practical embodiments of the same are illustrated. In the drawings,

Fig. 1 is a side elevation of one form of the means or device, and

Fig. 2 is a side elevation of the lower portion of another form of the means or device.

25 In the drawings the same reference numerals are employed to denote like parts.

Referring to Fig. 1 of the drawings, in which the complete means or device is illustrated, the numeral 1 denotes the frame or former, shaped more or less to the contour of the toe and lower and back portions of the sock. In this embodiment the frame or former 1 may be made of stout wire or metal rod and is shown of round section. 30 2 denotes the toe portion of the frame or former 1, 3 the sole portion, 4 the heel portion, and 5 the lower back and calf portion. Beyond the portion 5 the frame 1 is extended upwardly at 6, and then bent at 7 and shaped to provide the forwardly extending curved or arcuate portion 8. 35 At the end of the curved portion 8 it is bent or shaped to extend downwardly at 9, in the direction of the sole portion 3 to provide a hook from which it may be suspended. The frame 1, from the top of the toe portion 2, is shaped, as indicated 40 at 10, to extend in the direction of the heel 4 to a point 11 near said heel 4.

45 50 This construction of the device permits the sock or the like, whether in a wet or dry condition, to be easily and quickly placed upon the frame 1, and as readily removed therefrom after it has been stretched or shaped thereon, as hereinafter described.

55 55 12 is the cord or member which operates in conjunction with the frame 1 to stretch or shape the sock. It is passed downwardly through and

engages in a hole 13 in the upper side of the toe portion 2 of the frame 1, and thence passes to and downwardly through a hole 14 in the heel portion 4 near its junction with the sole portion 3, whence it passes to and upwardly through a further hole 15, then downwardly to and through another hole 16, and then upwardly to and through a still further hole 17. From the hole 17 the cord 12 is taken to a point 18 where it is tied or connected to the portion 19 thereof which passes to the hole 13, so that a triangle 20 is formed below the point of connection 18. From the point 18 the two portions of the cord 12 extend for a suitable distance upwardly, and the upper portions are knotted in two places at 21 and 22 to form a loop 23, and near their ends are connected by a preferably metal seal 24, which can be held between the finger and thumb in manipulating the cord 12.

The edges of the holes 13, 14, 15, 16 and 17 are all suitably rounded so as not to chafe the cord 12. The passing of the cord or member 12 through the holes 14-17 as shown ensures that said cord 12 will be locked against movement due to pull from either end, but allows of adjustment of the cord 12 by pulling the same through each hole separately in turn.

The triangular lower portion 20 of the cord 12 may be moved or adjusted to vary its interior angles, and so permit the position of the point of connection 18 to be varied or adjusted in relation to the upper part of the heel portion 4, to limit the stretching movement of the cord 12 at or about the position of the ankle.

In operation the cord 12 will first be loosened by moving the loop 23 (which is shown surrounding the forwardly extending portion 8 of the frame 1) backwards upon said portion 8 of the frame and over the bend 7. The sock is then arranged in position upon the frame 1, and the cord 12 pulled taut, and the loop then moved forwardly over the bend 7 on to the arcuate surface of the forwardly extending portion 8 sufficiently to shape the sock or stretch it to the desired extent. During this operation the portion 19 of the cord 12 serves to shape or stretch the upper or front foot portion of the sock, and the portion 23a of the triangle 20 serves to limit the stretching movement of the cord 12 at the ankle. In order to stretch the sock, in case it is wet and shrunken, the toe portion 2 of the frame 1 is pushed into the toe of the sock, and the shrunken heel gradually pulled over the heel portion 4 of the frame 1. The front of the sock is then stretched by pulling it, and the cord 12 then moved into position to retain the sock, under the necessary tension, in the stretched condition.

Knots 26, 27, are made in the portions 23a and 28 of the triangular portion 20 of the cord 12 which, by coming into contact with the frame 1 at the holes 17 and 14 respectively, operate as stops and limit the movement of the cord 12 in both directions when adjusting it. This will also permit of slackening of the cord 12 at the triangle 20 when stretching a sock that has shrunk in washing.

In the modified form of the invention illustrated in Fig. 2, the frame or former 1 is made of metal or material of flat shape in cross-section, and the holes for the reception of the cord 12 pass through the frame 1 from side to side thereof. In this construction provision is made for locking the cord 12 in the frame 1 at both the toe portion 2 and heel portion 4. For this purpose four spaced holes 29 are provided in the

toe portion 2, and four spaced holes 30 in the heel portion 4 to and through which the cord 12 is caused to pass, as shown.

This form of the invention, in which the frame is made of flat strip metal, will act to leave a pronounced crease or produce an ironed effect in the flat sock, when shaping or stretching the same, and will be especially useful to manufacturers for shaping and drying socks, stockings and the like after the same have been made, in which case they can be suitably arranged upon the device and thereafter sprayed, steamed or wetted to shrink and shape them thereon.

15 The frames or formers 1 in either of the above forms may be made of stainless steel, or other suitable non-corrosive metal, and be of any preferred and suitable shape in cross-section, or be galvanized, plated or otherwise treated to provide them with rustless surfaces. Alternatively, they may be made of plastic material and be constructed with a strengthening rib or web extending inwardly from a rounded outer portion, so as to afford strength without interfering with the drying of the sock.

20 If preferred the cord or member 12 may be made of resilient material, or elastic or spring means may be incorporated therein or combined therewith.

25 30 What I claim as my invention and desire to protect by Letters Patent is:

1. Means for stretching or shaping socks and similar foot coverings, including a frame shaped to conform substantially to the shape of the toe, 35 sole, heel and back portions of the sock or the like when in a flat condition, and extending forwardly at the top of the back portion, and a cord adapted, when in use, to extend from the toe portion of the frame to and engage with the forwardly extending portion thereof, and to be moved into position to apply tension to the front of the sock to cause it to be stretched or shaped upon and by the frame and said cord; said cord including a portion adapted to extend from the 40 forwardly extending portion of the frame to a point in the region of the ankle, a portion connecting the cord at such point to the toe portion of the frame and serving to stretch or shape the front of the foot of the sock, and a further portion connecting said cord at said point to the heel portion of the frame and serving to limit the movement of the cord in a forward direction at the ankle.

2. Means for stretching or shaping socks and similar foot coverings, including a frame shaped to conform substantially to the shape of the toe, sole, heel and back portions of the sock or the like when in a flat condition, and extending forwardly at the top of the back portion, and having 50 holes in its toe and heel portions, and a cord adapted, when in use, to extend from the toe portion of the frame to and engage with the forwardly extending portion thereof, and to be moved into position to apply tension to the front of the sock to cause it to be stretched or shaped upon and by the frame and said cord; said cord including a portion adapted to extend from the forwardly extending portion of the frame to a point in the region of the ankle and a triangular 55 part connecting said first-mentioned portion to the toe and heel portions of the frame and adjustable in the holes in the frame to vary the position of the triangular part and the angles thereof.

3. Means for stretching or shaping socks and similar foot coverings, including a frame shaped to conform substantially to the shape of the toe, sole, heel and back portions of the sock or the like when in a flat condition, and extending forwardly at the top of the back portion, and having holes in its toe and heel portions, and a cord adapted, when in use, to extend from the toe portion of the frame to and engage with the forwardly extending portion thereof, and to be moved into position to apply tension to the front of the sock to cause it to be stretched or shaped upon and by the frame and said cord; said cord including a portion adapted to extend from the forwardly extending portion of the frame to a point in the region of the ankle, a triangular part connecting said first-mentioned portion to the toe and heel portions of the frame and adjustable in the holes in the frame to vary the position of the triangular part and the angles thereof, and means for limiting the movement of the cord in the holes.

4. Means for stretching or shaping socks and similar foot coverings, including a frame shaped to conform substantially to the shape of the toe, sole, heel and back portions of the sock or the like when in a flat condition, and having an arcuate portion extending forwardly at the top of the

5 10 15 20 25 back portion, and a movable cord adapted, when in use, to extend from the toe portion of the frame to and adjustably engage with the arcuate forwardly extending portion thereof, and to be moved into position to apply tension to the front of the sock to cause it to be stretched or shaped upon and by the frame and said cord; said cord including a portion adapted to extend from the forwardly extending portion of the frame to a point in the region of the ankle, a portion connecting the cord at such point to the toe portion of the frame and serving to stretch or shape the front of the foot of the sock, and a further portion connecting said cord at said point to the heel portion of the frame and serving to limit the movement of the cord in a forward direction at the ankle.
